UNITED STATES PATENT OFFICE.

GEORGE HOWLETT DAVIS, OF WEST ORANGE, NEW JERSEY.

MUSIC-ROLL HOLDER.

No. 860,129.

Specification of Letters Patent.

Patented July 16, 1907.

Application filed April 27, 1907. Serial No. 370,599.

To all whom it may concern:

Be it known that I, GEORGE HOWLETT DAVIS, a citizen of the United States, residing at West Orange, in the county of Essex and State of New Jersey, have invented new and useful Improvements in Music-Roll Holders, of which the following is a specification.

My present invention relates to certain new and useful improvements in music roll holders especially designed for use in connection with player pianos and pianos having automatic playing attachments associated therewith.

The primary object of the invention is to provide a novel construction of roll holder designed to be movably mounted under the key-base of the musical instrument in such manner that the holder may be moved back under the key-base so as to be out of view when not in use, and may be moved out in front of the key-base when in operative position so as to cause the music sheet to travel in a nearly vertical plane.

20 The invention has for a further object to provide a novel construction and arrangement of mechanism for winding and rewinding the music sheet.

Briefly and generally stated the invention embodies a sliding element carrying the tracker or other 25 note selecting device and the take-up roll at its front end, and a swinging frame pivotally connected to the sliding element and designed to be swung upward at right angles thereto in front of the key-base and also designed to be swung parallel with said sliding element and then moved back under the key-base where it will be out of view and out of the way.

The invention further comprises the construction and arrangement of parts hereinafter described for winding and rewinding the music-sheet.

35 A preferred embodiment of the invention is illustrated in the accompanying drawing wherein—

Figure 1, is a side elevation of the music-roll holder shown in playing position on the key-base of a piano, the said key-base being shown in section—Fig. 2, is a similar elevation showing the holder moved back under the key-base—Fig. 3, is a detail side elevation showing an electric note selecting device. Fig. 4, is a detail top plan view partly in section of one side of the holder showing a part of the winding and rewinding mechanism for the music sheet. Fig. 5, is a front elevation looking in the direction of the arrow X—Fig. 1. Fig. 6, is a horizontal sectional view of the winding and rewinding mechanism.

Referring to the drawing the reference numeral 1 50 designates the key-board base of an ordinary piano having a self-playing mechanism associated therewith or of a player piano. Slidably mounted in suitable grooved ways formed in strips 2 secured to the under side of the key-board base is a plate 3 to the forward 55 end of which is secured a tracker 4, having the usual air ducts and from which lead the air tubes 5 usually

in the form of rubber pipes which communicate with the operating pneumatics. Secured to and depending from opposite sides of the plate 3 in rear of the tracker 4 are two brackets 6 in which is journaled a main driving shaft 7 which may be rotated clockwise as seen from the right hand side shown in Figs. 1 and 2 by any suitable mechanism. Also journaled in the brackets 6 at the forward ends thereof is a transverse shaft 8 carrying a take-up roller 9 for the music sheet, said take-up roller being located below the plate 3 and in rear of the tracker 4. The shaft 8 has fixed thereon a gear wheel 10 which is in mesh with a pinion 12 secured to the driving shaft 7 as more clearly shown in Figs. 4 and 6.

Pivotedly mounted at opposite ends of the shaft 8 so as to swing thereon are two arms 13 the upper ends of which are joined together by means of the curved guard plate 14 said arms carrying respectively the end bearings 15 for the delivery or music spool 16, some of said bearings being of the usual winged type 75 to receive the corresponding wing-journal on the music spool.

The end bearing 15 for the music spool, which it will be understood is journaled in one of the arms 13 is provided at its outer end with a sprocket wheel 17 80 and a handle extension 18 which sprocket wheel is geared, through the medium of a sprocket chain 19, with a sprocket wheel 20 journaled on the shaft 8. Formed integral with the sprocket wheel 20 is another and smaller sprocket wheel 21 geared by means of a 85 sprocket chain 22 with another sprocket wheel 23 carried by sleeve 24, which sleeve is loosely mounted on the driving shaft 7, said sleeve being held against longitudinal movement on the shaft 7 by means of a key 25 which may project within an annular groove formed 90 in the periphery of the sleeve, as more clearly shown in Fig. 6.

The driving shaft 7 is longitudinally movable in its bearings and has secured to one end thereof a handle 26 by which it may be shifted longitudinally and a 95 clutch member 27 designed to be brought into engagement with a co-operating clutch member 28 on the sleeve 24 when said shaft is moved longitudinally in the direction of the arrow Fig. 4.

When the music roll holder is in normal or inoperative position the sliding plate 3 is back under the key-board base and the arms 13 carrying the end bearings for the music spool are swung up parallel with the plate 3 as shown in Fig. 2, the arms being held in the position shown by any suitable retaining device as for 105 instance a spring 29 as shown in Figs. 1 and 2. When in this position the music roll holder will be out of view and out of the way of a performer when seated at the piano. When it is desired to bring the music roll holder in position for operation the slide 3 is drawn out 110 until the tracker 4 assumes a position in front of the key-board base 1, whereupon the arms 13 are swung

up in the position illustrated in Fig. 1 where it will be seen that the music spool 16 will be directly in front of the key-board and the music sheet 30 during its travel over the tracker 4 and onto the take-up roller 9 will move in a nearly vertical direction in front of the performer when seated at the piano. The frame is held in its operative position by means of a spring catch 31, secured to the plate 3, which catch is designed to be brought into engagement with a pin 32, 10 projecting from one of the arms 13 of the swinging frame.

The take-up roller 9 is driven to wind the music sheet thereon by means of the shaft 7, pinion 12 and gear wheel 10.

15 When it is desired to rewind the music sheet from off the take-up roller 9 onto the music or delivery spool 16 the shaft 7 is moved longitudinally in the direction of the arrow Fig. 4 which will throw the pinion 12 out of mesh with the gear 10 bringing the clutch elements 27 and 28 into engagement. As the shaft 7 now continues to rotate in its clockwise direction rotary motion will be imparted from the sprocket wheel 23 to the wheels 21 and 20 and through the latter to the sprocket wheel 17 which will cause the music spool to wind in the opposite direction whereupon the music sheet will be rewound thereon.

In Fig. 3 I have shown the invention as applied to playing mechanism controlled electrically instead of pneumatically and instead of employing the ordinary 30 tracker 4 having the usual wind ducts, I employ an electric selecting device embodying a contact roller 42 journaled in arms 33 projecting outward from the plate 3, and selector-fingers 34 which coöperate with the contact roller 42, said selector-fingers being carried by a rail 35 secured in position by means of arms 36 attached to the swinging arms 13.

I do not wish to be understood as limiting myself to the precise construction and arrangement of parts herein shown and described except as I may be so 40 limited by the terms of the appended claims, as I am aware that changes and additions may be made in the construction herein shown and described without departing from the spirit of the invention.

Obviously any arrangement of mechanism may be 45 employed with my improved music roll holder for winding and rewinding the music sheet, that shown being only by way of example. The principal feature of the invention resides in a music roll holder embodying a sliding member arranged to be moved back and forth beneath the key-board base of the piano, said sliding member carrying a swinging frame provided with end bearings for a music spool, said swinging frame being designed when the sliding member is in its outer position, to assume a position in front of the key-board 50 base and also designed to assume a position beneath and parallel with the sliding member and adapted to be moved back under the key-board base where the holder will be out of view and out of the way.

What I claim is

60 1. In combination with a suitable support, a member slidably mounted thereon, a note-selecting device and a take-up roll carried by said sliding member, a frame having a swinging connection with the said member and adapted to be swung up at substantially right angles thereto and also movable to a position parallel therewith, and end-bearings for a music spool carried by said frame.

2. In combination with the key-base of a piano, a member slidably mounted beneath the base and carrying a note-selecting device at its forward end, a take-up roll also carried by said member, a frame having a pivotal connection with the sliding member and adapted to assume positions at an angle thereto and parallel therewith, and end-bearings for a music-spool carried by the pivotal frame. 70

3. In combination with the key-base of a piano, a member slidably mounted beneath the base carrying a tracker at its forward end, a take-up roll supported from the sliding member in rear of the tracker, a swinging frame pivotally connected to the sliding member, and end-bearings for a music-spool carried by the swinging frame. 75

4. In combination with the key-base of a piano, a take-up roll slidably supported beneath the base, a swinging frame pivoted on the axis of said roll, end-bearings for a music spool carried by the swinging frame, and a note-selecting device. 80

5. In combination with the key-base of a piano, a take-up roll mounted to slide back and forth beneath the base, a tracker in advance of the take-up roll, a swinging frame pivoted on the axis of said roll, and end-bearings for a music spool carried by the swinging frame. 85

6. In combination with the key-base of a piano, a take-up roll mounted to slide back and forth beneath the base, a tracker in advance of the take-up roll, a swinging frame pivoted on the axis of said roll, end-bearings for a music spool carried by the swinging frame and means for driving the take-up roll to wind a music sheet thereon. 90

7. In combination with the key-base of a piano, a plate slidably mounted beneath said base and having a tracker at its front end, brackets depending from the plate in rear of the tracker, a take-up roll journaled in said brackets, a pair of swinging arms pivotally connected to the brackets, and end-bearings for a music spool carried by said arms. 95

8. A music roll holder embodying a sliding member, a tracker and a take-up roll carried thereby, and a swinging frame carrying end-bearings for a music spool pivotally connected to said sliding member. 100

9. In combination with the key-base of a piano, a member slidably mounted beneath said base, said member carrying a tracker and a take-up roll, a swinging frame pivotally connected to the sliding member and adapted to assume positions at right angles thereto and parallel therewith, end-bearings for a music-spool carried by the swinging frame, a power shaft and gearing between said shaft and take-up roll and one of said end-bearings. 110

10. In combination with the key-base of a piano, a member slidably mounted beneath said base, said member carrying a tracker and a take-up roll, a swinging frame pivotally connected to the sliding member and adapted to assume positions at right angles thereto and parallel therewith, a music spool carried by the swinging frame, a power shaft and interconnecting gearing between said shaft and roll and spool for winding and rewinding a music sheet. 115

11. In combination with the key-base of a piano, a member slidably mounted beneath said base carrying a tracker and a take-up roll, a swinging frame pivoted to the sliding member and adapted to assume positions at right angles thereto and parallel therewith, end-bearings for a music spool carried by the swinging frame, a power shaft journaled in bearings on the sliding member and gearing between said shaft and take-up roll. 120

12. In combination with the key-base of a piano, a member slidably mounted beneath the base carrying a tracker and a take-up roll, a swinging frame pivoted to the sliding member and adapted to assume positions at right angles thereto and parallel therewith, end bearings for a music spool carried by the swinging frame, a longitudinally shiftable power shaft journaled in bearings carried by the sliding member, gearing between said shaft and take-up roll, and clutch-controlled gearing between the shaft and one of said end-bearings. 125

13. In testimony whereof I have hereunto set my hand in presence of two subscribing witnesses.

GEORGE HOWLETT DAVIS.
